LADY'S UTILITY BAG

Thomas W. Spradling, Sappington, Mo.

Application April 6, 1953, Serial No. 24,356

Term of patent 3½ years

(Cl. D87—3)

To all whom it may concern:

Be it known that I, Thomas W. Spradling, a citizen of the United States, residing at Sappington, in the county of St. Louis and State of Missouri, have invented a new, original, and ornamental Design for a Lady's Utility Bag, of which the following is a specification, reference being had to the accompanying drawing, forming a part hereof.

Fig. 1 is a top view of a lady's utility bag embodying my new design, the bag being shown as closed.

Fig. 2 is a front view of the bag.

Fig. 3 is a side view of the bag.

A portion of the handle has been eliminated in Figs. 1 and 2 of the drawing for convenience of illustration.

I claim:

The ornamental design for a lady's utility bag, as shown and described.

THOMAS W. SPRADLING.
